S. B. DAVIS.

ADJUSTABLE MOLD FOR BUILDING CONCRETE STRUCTURES.
APPLICATION FILED DEC. 10, 1913.

Patented Aug. 14, 1917.

UNITED STATES PATENT OFFICE.

SOLOMON B. DAVIS, OF SHAWNEE, OKLAHOMA.

ADJUSTABLE MOLD FOR BUILDING CONCRETE STRUCTURES.

1,236,824.

Specification of Letters Patent. Patented Aug. 14, 1917.

Application filed December 10, 1913. Serial No. 805,754.

To all whom it may concern:

Be it known that I, SOLOMON B. DAVIS, a citizen of the United States, and a resident of Shawnee, in the county of Pottawatomie 5 and State of Oklahoma, have invented certain new and useful Improvements in Adjustable Molds for Building Concrete Structures, of which the following is a specification, reference being had to the accompanying drawings.

This invention relates to certain new and useful improvements in molds for building concrete structures; and the primary object of my invention is to provide an adjustable 15 form or mold, especially adapted to be used in building monolithic structures.

Another object is to provide an adjustable mold, of a simple and inexpensive nature and of a compact and durable construction, capable of accurate adjustment to enable an operator to build monolithic structures, the thickness of the walls and horizontal reinforcements of which are automatically increased with the increase in size 25 of structure of polygonal form.

A further object is to provide a silo mold including a number of inner and outer form plates, which may be adjusted to form structures in the form of a regular polygon of 30 different diameters, and thickness of walls.

Another object is to provide a mold or form which can be arranged to be used in building structures having rectangular corners.

With these and other objects in view the present invention consists in the combination and arrangement of parts as will be hereinafter more fully described and finally pointed out in the appended claim, it being 40 further understood that changes in the specific structure shown and described may be made within the scope of the claim without departing from the spirit of the invention.

In the accompanying drawings forming a part of this specification and in which like numerals of reference indicate similar parts in the several views:

Figure 1, shows a top view of two connected inner and two connected outer plates 50 as used in my invention, disclosing a locking

bar and the door jamb the former in position.

Fig. 2, is an elevation of two inner connected plates showing two release plates as 55 connected.

Fig. 3, shows a fragmentary top view of two connected plates arranged in a straight line and held in position by means of a locking bar.

Fig. 4, shows a complete form or mold disclosing the location of the release plates.

Fig. 5, shows a perspective view of four release plates secured to form a rectangular wall corner.

Fig. 6, shows a sectional view of the inner and outer plates.

Fig. 7, shows respectively an edge and face view of one of the expanding strips.

In carrying out the object of my invention, I employ a mold including two forms, one comprising a set of similar outer flanged plates, and a set of similar inner flanged plates, these sets of plates when connected in one manner forming a regular polygon, 75 the inner plates being of a predetermined shorter length than the outer. The form plates are flat and are interchangeable. The inner set further includes a form plate including a major and minor section, which 80 are detachably united and form what I term the release plates, the combined length and width of two connected release plates being equal to that of a regular inner plate.

As shown in the drawings each inner form 85 plate A which is flat, is provided with an upper flange 1, a base flange 2, and two similar end flanges 3, 3. As shown in Fig. 1, these end flanges form an acute angle with the face of the plates, the angle of these end 90 flanges 3, in practice being extended approximately at eighteen degrees to the face of the plate. The inner form is provided with one plate forming a release plate and comprising a major plate section B and a minor plate section B', shown in top view 95 as connected in Fig. 1. The major plate section B has its flange 3, subtending at 18° while the opposite releasing flange 5, is held at an angle of 45°. The minor plate section 100 B' has a release flange 4, subtending at 135° to the base of the plate, as shown in Fig. 1,

so that when said release flanges 4 and 5 are connected, the major and minor sections are held in alinement. In Figs. 1 and 2, these plates are shown as having their release flanges connected by means of the bolts B³.

Each outer plate C is provided with a top flange 1' and a bottom flange 2' and two end flanges 3'.

As these outer and inner form plates are 10 made of thin sheet steel it is desirable to have their upper and lower flanges reinforced to strengthen the same, and this I accomplish in continuing the metal from the flanges 1 and 1' to form a double thickness 15 a, which is continued in the end flange b, held against the plates, as shown in Fig. 6. Near each end the top and bottom flanges of each plate are provided with suitable bolt openings 6, while the end flanges 3 and 20 3' have the openings 7.

The length of the inner plates A, and connected release plates B', B are of a predetermined length relative to the length of the faces of the outer form plates C.

25 As shown in Fig. 1, when the inner plates are connected in such a manner that the faces of the edge flanges 3, 3' are held in juxtaposition, the end flanges 3' of the outer plate C are held in divergent spaced relation. In Figs. 1 and 2 the inner plate are 30 shown as connected by means of the bolts A B while the outer flange 3' is connected by means of a bolt C². As shown in Fig. 1, these flanges 3' extend at right angles to 35 the faces of the plates.

In Fig. 4, I have shown a mold comprising 40 12 united inner form plates and 12 united outer form plates. The wall between these two sets of form plates will be of a predetermined thickness. Now should 13 inner, and 13 outer form plates be employed, there would be a corresponding increase in 45 thickness of the wall formed between the greater number of form plates. The distance between the sets of form plates increases as the number of plates is increased.

In building a wall, the inner and outer 50 form plates must be held in parallel spaced relation to each other and in order to hold these inner and outer face plates in proper position, I employ what I term a locking bar D, which has one end recurved to form a hook 9, arranged to fit and clasp over an outer flange 1', while a U-shaped sliding 55 jaw D' is slidably held upon its member. This locking bar D near its hook end has a number of bolt openings 10, and near its opposite end the wedge seats D⁴ as well as the bolt slots D³. A wedge D² fits into the 60 wedge seats to hold a set of inner and outer plates in accurate parallel spaced relation.

After the walls have been molded the outer 65 form plates can be removed in releasing the bolts C². Before the inner plates however can be released the bolts B³ must be removed

so that the minor sections B' can be swung inwardly, after which the major section B can be swung inwardly, permitting the ready removal of the remaining sections A.

There is a special reason in providing the 70 release plate B and B' of different lengths as will be set forth more fully hereinafter.

If it is desired to decrease the thickness of the wall after having reached a desired height, it is simply necessary to insert one 75 of the battens or expanders G between each set of inner plates. This will result in decreasing the thickness of the wall. As shown in Fig. 7 these battens or expanders have suitable openings arranged to receive 80 the bolts A B, which are employed to connect the inner end flanges 3.

Where it is desired to build a square structure I disconnect the major and minor plates B and B' and reverse these members and 85 connect them so that a right angle can be formed as is shown in Fig. 5. Two members B are connected to form the inner mold forms and two larger or major sections B' to form the outer plates of the mold. When 90 this is done the corners are brought into alinement and a wall will be formed between the two members of a predetermined thickness.

Where the plates B and A are connected 95 as shown in Fig. 2, the flanges of the plates are connected at their top by means of a locking bar D. In this construction a bolt 12 is used passing through one of the openings 10, while a second bolt 12 is made to 100 pass through the slot D³. From the foregoing it will be noticed these locking bars D are not only used in holding the inner and outer mold members in parallel spaced relation, but are also used in holding the different plates in alinement, where they are used to form square corners. Where the locking bars D are used to hold plates in alinement the sliding jaw D' is of course not employed. As set forth the doors are of the refrigerator 110 type and if desired can be continuous or be arranged at intervals.

Further as described the thickness of the walls and the efficiency of the horizontal reinforcing increases automatically with the 115 increase in size of the silo. Any desired thickness of wall can further be secured by the use of the expander G.

Having thus described my said invention what I claim as new and desire to secure by 120 United States Letters Patent is:

An adjustable mold for building concrete structures comprising an outer and an inner plate held in parallel spaced relation, each made of thin sheet metal and provided with 125 an upper and a lower flange extending at a right angle, each flange being of a double thickness and ending in an edge held against its plate, a locking bar which has one end recurved to form a hook arranged to clasp 130

over one of said upper flanges, a U-shaped jaw slidably held upon said locking bar, arranged to engage an opposite upper flange said locking bar having a plurality of wedge seats, and a wedge adapted to work through

5 said wedge seats and against said U-shaped jaw to hold said plates in spaced relation.

In testimony whereof I affix my signature in the presence of two witnesses.

SOLOMON B. DAVIS.
